AUTOMATIC CAR-COUPING.

No. 849,042.

Specification of Letters Patent.

Patented April 2, 1907.

Application filed November 3, 1905. Serial No. 285,750.

To all whom it may concern:

Be it known that I, THOMAS G. BLACKMAN, Jr., a citizen of the United States, residing at Graceville, in the county of Jackson and State of Florida, have invented new and useful Improvements in Automatic Car-Couplers, of which the following is a specification.

My invention relates to improvements in automatic car-couplers comprising a knuckle which swings in a horizontal plane and a locking pin or abutment in the head which functions as a lock-set and knuckle-opener and is so constructed and disposed that it is positively forced into locking position by the incoming knuckle.

It is the object of my invention to provide a coupling which shall possess the maximum durability and strength and with but two movable parts act to lock, set, and open the knuckle positively. I propose to use an angular locking device loosely pivoted in the draw-head and disposed centrally thereof. The device swings on its pivot in a substantially vertical longitudinal plane through the coupling, its lower end being disposed in the path of the incoming knuckle-shank and engaged thereby to force its upper end between shoulders on the head and shank, thereby locking the latter against outward movement. The operating rod or chain for the device is connected thereto at the outer portion of its upper end, so that it acts both to rock the device on its pivot and also to lift it bodily. The first movement locks the knuckle, the second causes a shoulder on the device to catch on a portion of the knuckle-shank and set the device for uncoupling. If the lifting movement of the device be continued, it will be rocked on its pivot upon reaching the end of its vertical play, which movement brings its lower end into positive engagement with the knuckle-shank in a manner to force or prize it outwardly to open the knuckle.

The above ends are best attained by the construction and arrangement of parts hereinafter more particularly described and constituting a part of my invention, to which, however, I do not desire to be limited.

Referring to the drawings, which illustrate the preferred embodiment of my invention, Figure 1 is a horizontal-sectional view through a draw-head, illustrating the locking device in coupled position. Fig. 2 is a vertical sectional view taken along the line $x-x$ of Fig. 1,

showing the locking device in coupled position. Fig. 3 is a view similar to Fig. 2, showing the locking device set for uncoupling. Fig. 4 is a view similar to Fig. 2, illustrating the manner in which the locking device acts as a knuckle-opener, the knuckle standing in open position ready for coupling. Fig. 5 is a front view with the knuckle broken away along the line $y-y$ of Fig. 1. Fig. 6 is a detail plan view of the knuckle. Fig. 7 is a side elevation of Fig. 6 looking from the right.

Similar reference-numerals refer to similar parts throughout the drawings.

In its preferred form I have illustrated my invention as applied to a draw-head 1, having a transverse horizontal recess, into which the shank 2 of the knuckle 3 is adapted to swing. The draw-head is provided with ears 4, between which the knuckle is pivoted at or near its central point by a pin 5. The shank is formed so that a portion of it stands flush with the outer concave face of the draw-head when in a coupled position. To this extent my present invention proposes to embody the advantages and improvements claimed in Letters Patent No. 502,274, granted to me on the 1st day of August, 1893. When the knuckle is in its coupled position, the rear side of the shank engages the inner wall of the recess on the draw-head, thereby making the construction very compact and requiring only a minimum amount of metal to be taken out of the draw-head for the reception of the knuckle-shank and locking devices.

My improved locking means for the knuckle comprises an integral locking device 6, disposed within a vertical recess 23 in the head and substantially semicircular in shape. The particular configuration of this locking member may be varied in many ways, the essential features of its construction consisting in the angular disposition of its upper or locking end or head 7 and its lower end or tailpiece 8 with relation to the elongated pivot-opening 9. A pin 10, serving as a pivot for the locking device, is passed transversely through the head and through the elongated opening 9. The end 7 of the device is bifurcated, and a rod 11 is pivotally connected therein in any suitable manner. This rod projects through an opening 12 in the top of the head, where it is connected to suitable operating devices, such as a lever 13. The

locking device is provided with a lock-set projection or shoulder 4 between its ends 7 and 8.

The knuckle is provided with a shank of peculiar configuration comprising a slanting face 15, commencing at the point 16 at the front of the knuckle and slanting from this point back to a point 17. The point 16 forms the apex of a shoulder 18, which tapers down to the point 17, which is above the plane of the reduced end 19 of the shank. From the point 17 the shank is provided with a vertical face leading from the slanting face 15 down to a recess or groove 20, extending to the end of portion 19 of the shank on its rear side. The bottom wall or floor of this recess slants inwardly, as best seen in Figs. 2 and 3.

In operation if the parts be taken in their coupled position, as seen in Figs. 2 and 4, it will be evident that the end 7 of the locking device is disposed between the shoulder 18 of the shank and a shoulder 21 of the head, this shouldered portion being disposed above the end 19 of the shank and having its vertical wall disposed substantially parallel to and separated several inches from the shoulder 18 of the shank. As seen in Fig. 4, the end 7 of the locking device is disposed between these two shoulders, and it thus opposes the outward movement of the shank with its full crushing strength. When in this position, the shoulder 14 rests against the rear side of the shank, and the lower end 8 of the device swings free of the shank in the recess 22, which forms a continuation of the narrow vertical chamber 23, Fig. 1, in which the locking device is disposed. To permit the knuckle to open for uncoupling, the locking device is lifted by the rod 11 until its end 7 is lifted clear of the shoulder 18. As it moves to this position it is lifted bodily until the shoulder 14 rises above the recess 20 in the rear side of the shank. The action of the rod 11 in lifting the locking device against its pivot-pin 10 will draw the shoulder 14 outwardly, so that its tapering bottom will rest upon and be held by the slanting floor of the recess if the rod is released. This leaves the locking device in the position shown in Fig. 3, where the knuckle is still in coupled position, as shown in Fig. 2. The shoulder 14 thus holds the locking device in a position for uncoupling, and therefore constitutes what is termed a "lock-set." When the locking device is in the position shown in Fig. 3, the shank is free to swing outwardly, as the tapering face 15 of the shank will pass under the head 7 of the device, which will be lifted slightly as the slanting floor of the recess 20 moves out from under the shoulder 14. Upon the disengagement of the shoulder 14 from the shank the end 7 of the locking device falls upon the slanting face 15 of the shank and rests thereon. As the shank

is moved inwardly the face 15 passes from under the end 7 of the locking device, and immediately thereafter the rear side of the shank strikes the shoulder 14 of the locking device, forcing the locking device positively to its locking position between the shoulders 18 and 21. By raising the rod 11 the lower end 8 of the locking device will be brought into engagement with the lower beveled edge 24 of the shank portion 19 and will force the knuckle outwardly to its open position. By holding the operating-lever 13 the device will prevent the rebounding of the knuckle.

It will be noted that when the parts are in coupled position the draw-head, with the exception of the narrow vertical recess 23 for the locking device, is substantially solid. This is best seen in Fig. 4, and it will be evident that my invention requires the least possible amount of metal to be taken out of the head and at a point where it effects its strength least. The manner in which the shank rests against the rear wall of the recess and stands flush with the face of the head gives the head practically the same strength to resist jamming as if the parts were integral. It is also to be noted that the locking device is disposed so as to be operated from the center of the head, which is considered a point of advantage in practice over devices which are operated from the sides of the head.

The free manner in which the locking device is pivoted enables it to jump away from the shank when it is struck a violent blow, which is of great advantage in preserving the locking device against breakage. However, the locking device may be rigidly connected to its pivot-pin 10, which latter may be extended to the side of the head and be provided with a crank by means of which the locking device may be operated from the side of the car and without using the rod 11 and lever 13 for this purpose.

Having thus described my invention, what I claim as new, and desire to secure by Letters Patent, is—

1. An automatic coupling comprising a recessed draw-head, a knuckle pivoted thereto and provided with a shank adapted to swing into the recess in said head, shoulders on said head and shank, and a locking device disposed in said head and adapted to be engaged by said shank as it moves inwardly to couple and forced thereby positively and independently of gravity between said shoulders to complete locked position, substantially as described.

2. An automatic coupling comprising a recessed draw-head, a knuckle pivoted thereto and provided with a shank adapted to swing into the recess in said head, a rocking angular locking device disposed in said head and adapted to be engaged by said shank as it moves inwardly and swung thereby in a verti-

cal plane longitudinally of the head until it is forced by said shank positively and independently of a gravity movement between portions of the head and shank to complete 5 locked position.

3. An automatic coupling comprising a recessed draw-head, a knuckle pivoted thereto and provided with a shank adapted to swing into the recess in said head, an angular locking device loosely pivoted in the head and having one end disposed in the path of said shank when in its open position and the other adapted to move toward the face of the head, and portions of the head and shank between 15 which said latter end is positively forced by the incoming shank independently of a gravity movement to complete locked position.

4. An automatic coupling comprising a recessed draw-head, a knuckle pivoted thereto 20 and provided with a shank adapted to swing into the recess in said head, the rear side of said shank abutting throughout against the rear wall of said recess while the front side of the shank stands flush with the concave face 25 of the draw-head, shoulders on said head and shank, and a locking device disposed in said head and adapted to be engaged by said shank and forced thereby positively to complete locked position between said shoulders, 30 substantially as and for the purposes described.

5. An automatic coupling comprising a recessed draw-head, a knuckle pivoted thereto and provided with a shank adapted to swing 35 into the recess in said head, said shank having a reduced portion leaving a shoulder, a shouldered portion of the head forming part of the top of said recess and under which said reduced portion of the shank passes, said shank 40 in its coupled position substantially filling the recess in the head, its rear edge throughout abutting against the rear wall of the recess and the major portion of its front edge standing flush with the face of the draw-head 45 and a locking device disposed in the head and adapted to be moved positively by said shank into the narrow opening between the said shouldered portions of the shank and head to lock the knuckle.

50 6. In an automatic coupling comprising a recessed draw-head, a knuckle pivoted thereto and provided with a shank adapted to swing into the recess in said head, said shank having a recess therein with an outwardly 55 and downwardly slanting floor, a locking device adapted to be moved in an arcuate direction by the shank and forced into position to lock the latter, and means to lift said device so that it engages in said recess in the 60 shank and is held thereby out of operative position for locking the shank.

7. In an automatic coupler, a draw-head

having a shallow horizontal recess in its front face and a narrow vertical recess disposed longitudinally of the head and opening into 65 said first recess, a knuckle pivoted to the head, a tail-wing on the knuckle which swings into said horizontal recess and has its rear edge to conform with and engage the rear wall of the horizontal recess, an angled locking device loosely pivoted in said vertical recess and so disposed that when in its open position its lower arm projects into the horizontal recess, and shoulders on said head and shank which stand opposed when the knuckle 70 is closed, the upper end of said locking device being adapted to be forced to complete locked position between said shoulders and held there by the engagement of the shank with its lower arm.

8. In an automatic coupler, a recessed draw-head, a knuckle pivoted therein, a shank on said knuckle having a shoulder 18, a slanting face 15 and a longitudinal recess 20, a shoulder 21 on the head opposed to shoulder 18, a locking device consisting of an angled piece having a locking-head, tailpiece and an intermediate shoulder, and means to lift said device so as to set its shoulder into said recess 20 thereby setting the device for 90 uncoupling, said device being so disposed and shaped that when the knuckle is open, its locking-head will rest on face 15 and as the knuckle closes, its shank will engage the tailpiece of the device immediately after the locking-head clears the face 15 and will force and positively hold said locking-head between the shoulders 18 and 21 until the device is lifted by said means.

9. In an automatic coupler, the combination with a draw-head and swinging knuckle, of a rocking locking device comprising a head, a tailpiece and a shoulder disposed toward the face of the draw-head, means to move said device, a tail-wing on the knuckle having a shoulder 18 and a slanting face 15, a shoulder on the draw-head opposed to the shoulder 18, said tail-wing being adapted to engage the tailpiece of said device and force its head positively between said opposed shoulders, and said shoulder on the locking device being adapted to be moved into engagement with said shank and thereby hold said head in a position to clear said shoulder 18 and rest upon said face 15 as the knuckle 110 opens.

In testimony whereof I have hereunto set my hand in presence of two subscribing witnesses.
